LUMINAIRE OF THE WALL MOUNTED TYPE

YEarl S. Wince, Newark, Ohio, assignor to Holophane Company, Inc., New York, N. Y., a corporation of Delaware

Application August 16, 1949, Serial No. 110,579

11 Claims. (Cl. 240—73)

1

The present invention relates to luminaires of the wall mounted type and is more particularly directed toward luminaires suitable for use as bed lights in hospitals.

The present invention contemplates a wall mounted type luminaire having an upper, sloping light transmitting and redistributing plate, and a lower, sloping light transmitting and redistributing plate, the plates converging toward one another accepting light radiating from a light source between the plates and transmitting the light rays with change of direction to produce light beams with the maximum intensity oblique, one beam for ceiling illumination and one for illumination of a work area below the luminaire—for example, the reading area for the occupant of a bed with the head of the bed under the luminaire. The luminaire is provided with an opaque housing extending between the plates on all sides thereof so that all light which escapes must pass through the plates. Inasmuch as such light transmitting and redistributing plates would be in the normal line of view for persons facing the wall on which the luminaire is mounted or looking lengthwise of the room, the surfaces of these plates would appear luminous in all directions of observation, and the present invention contemplates providing suitable screens extending far enough above and below the plates to cut off the plates from observation in limited regions both above and below the horizontal. In this manner the stray light escaping from plates of luminaires mounted along one wall of a room is cut off so as to avoid annoying glare to occupants of beds along the opposite wall.

The present invention also contemplates luminaires for the general purpose above set forth wherein each luminaire has a shiftable screen or shutter by which it is possible to cut off all downward light or all upward light or selected portions of the downward or upward light, or to allow all the light which the luminaire can deliver to escape upwardly and downwardly. This provides for flexibility of use and control by the occupant of the bed or the hospital staff.

The accompanying drawings, show, for purposes of illustrating the present invention, one embodiment in which the invention may take form, it being understood that the drawings are illustrative of the invention rather than limiting the same.

In the accompanying drawings:

Figure 1 is a top plan view of the luminaire with parts broken away on the line 1—1 of Fig. 2, showing interior construction;

2

Figure 2 is a vertical sectional view on the line 2—2 of Fig. 1;

Figure 3 is a transverse sectional view on the line 3—3 of Fig. 2;

Figures 4 to 7 are outline views illustrating the disassembled luminaire, Figures 4 and 6 being end elevational and top plan views of the portion of the luminaire normally permanently attached to the wall; and Figures 5 and 7 being end elevational and top plan views of the detachably carried housing;

Figure 8 is a perspective view of the complete luminaire; and

Figure 9 is a diagrammatic view illustrating it in use above the bed and showing the light distribution.

In the drawings, a wall is indicated at W and a wall carried outlet box at B. The backplate 10 has rearwardly extending end flanges 11 and 12 which reach back to the wall W to form a rear vertical ventilating flue F1. The plate 10 also has forwardly extending top and bottom flanges 13 and 14. The backplate 10 carries a splicing box indicated at 15 adapted to be secured to the outlet box in any convenient manner. The backplate also carries a forwardly extending bracket 16 to support a lamp socket 17, and two forwardly extending brackets 18 and 19. The bracket 19 carries a headed bolt 20 provided with a nut 21, the bolt 20 carries a spring 20' pressing against a ring 22 with an outer drumlike surface 23 and flange 24. The bracket 18 carries a ring 25 of L-shaped cross-section which forms a bearing for a flanged ring 26. The parts carried by the brackets 18 and 19 center about the axis 28, 28 of the lamp socket 17.

The members 24 and 26 support a sheet metal shutter 27 which occupies substantially 120° of arc about the axis 28, 28. This shutter is preferably cylindrical in the cross-section and may be shifted about on the bearing members by pull chains 29, 30 secured to the shutter as indicated in Figures 1 and 2. The shutter 27 is provided with an upper flange 31 and a lower tab 32 engageable with a bracket 33 carried by the backplate 10 to limit the movement of the shutter.

The wiring is brought in from the outlet box B to the splicing chamber 15 and through a cover 35, and is connected to lamp socket 17 and pull chain switch 36 as indicated at 36a, 36b, 36c. In the construction shown, the socket 17 is of the screw threaded type adapted to support a single incandescent lamp 37, preferably a 150 watt lamp.

55 The detachable housing indicated generally by

the reference character 40 has an outer ornamental sheet metal band with ends 41, 42 and front portion 43. It is slightly longer and deeper vertically than the backplate and receives a rearwardly opening, inner lamp box. This lamp box is formed by an upper sloping plate 45, a lower sloping plate 46, a front plate 47 and two side plates 48 and 49 welded together. The side plates 48 and 49 are offset as indicated at 48', 49' and welded to the ornamental housing as indicated at 50 (Fig. 1). The front wall 47 of the lamp box carries bracket strap indicated at 51, and welded to the front wall 43 of the ornamental band. The box and band form a housing detachable as a unit. The housing, together with the sides and front of the lamp box, form side ventilation flues F2 and F3 and a front ventilation flue F4 so that convection currents through all the flues dissipate the heat from the lamp and keep the lamp box from getting excessively hot. They also keep the housing at safe and acceptable temperatures. The front wall 47 carries a bracket 53 which receives a strip 54 adapted to extend into the path of the shutter 27 and act as a screen as will be described.

The detachable housing unit, when completely assembled, is indicated in Figs. 5 and 7. It may be secured to the wall mounted element or unit shown in Figs. 1 and 3 by screws indicated at 55, these screws passing through the top and bottom plates 45 and 46 of the lamp housing and the forwardly extending flanges 13 and 14 of the backplate.

The upper plate 45 is provided with a rectangular lens opening 56 and the lower plate 46 with a similar lens opening 57. The upper plate and front plate carry lens supporting shelf brackets 58 and 59, and the lower plate 46 carries a lens supporting strip 60. The lens openings 56 and 57 in the top and bottom plates of the lamp box receive light transmitting and redistributing plates preferably in the form of prismatic lenses having two parts as indicated at 70, 71 in the drawings. These lenses are rectangular and in the design shown are of a length to accept as much light from the substantially point source of the lamp bulb 37 as conveniently can be redirected prismatically into useful directions. They are of a width to intercept a wide beam of light in planes normal to the wall.

As shown in the drawings, the lens plates are alike and slope at an angle of approximately 15° to the horizontal. The inner lens member 70 is provided with light concentrating prisms concentric about an axis 70a normal to the plate. The plate is so mounted that the line connecting the light center or locus 1 with the center of the prism system of the nearer lens makes an angle of approximately 5°.

Due to the tilting of the lens and the position of the locus of the light rays, the inner plate 70 is adapted to receive light rays making angles of substantially 55° to zenith on the side remote from the wall and 25° from zenith on the side near the wall, with greater angles than these lengthwise of the rectangular plate. The refracting power of the prisms is such as to substantially converge the light so that it appears to come from the virtual center more remote from the plate.

The second component of the lens system, namely, the plate 71, is provided with parallel prisms 72 of such refracting power as to accept the light transmitted through the prisms of the first plate and bend this light into angles of sub-

stantially 50° from the nadir. All the prisms may be such as to achieve uniform slope angle of the rays. As shown, however, the front portion of the plate 71, i. e., in the region 73, has prisms 73a with a deviating power for light received from the first lens, such that the emitted rays of the front edge of the plate are somewhat steeper, as indicated at 74, to avoid being pocketed behind the housing.

As more clearly shown in Fig. 3 of the drawings, the ornamental housing 40 extends above and below the lens plates at the front of the lens plates and at the ends of the luminaire. This construction screens the lens plates from observation at angles in the region of the horizontal and a few degrees above and below the horizontal, so that when one looks at the fixture from across the room or lengthwise of the room, no annoying bright sources are visible.

In use, the luminaire is preferably mounted on the wall W above the hospital bed (and occupant) indicated in Figure 9 at 88 for illuminating the reading task at 81. The luminaire L on the wall above the head of the bed produces upwardly and downwardly directed oblique beams of light as indicated by the full line photometric curves 82 and 83. These slope away from the zenith and nadir to have a maximum intensity at an angle of 50° from the zenith and from nadir respectively.

An incandescent lamp of the size suitable for use in such a fixture has a filament which occupies a region of substantial size so that light from the comparatively large filament converges on points on the lens at angles of approximately 10° each side of the central ray. Owing to this, the luminaire is able to provide a lighting distribution with sufficient lateral and longitudinal spread to satisfactorily illuminate a reading task of the size likely to be required by the patient in the bed, even though the mounting height is comparatively low. For example, with a mounting height of approximately 6 ft. 8 inches, the luminaire with a 150 watt lamp will give a 25 ft. candle average illumination over a full newspaper page held by the occupant of the hospital bed in the ordinary reading position, and the minimum intensity will be more than 75 per cent of the average.

Whenever it is desired to cut off the downward component of light, it is possible to shift the shutter from the full line position shown in Fig. 3 to the dotted line position shown to position the shutter between the lamp and the lower plate. If, instead, it is desired to cut off the ceiling illumination, the shutter is shifted to the other position to place it between the lamp and the upper plate. When in either of these extreme positions, the light baffle strip 54 intercepts back reflected light from one lens plate so that it does not fall on the other for transmission through it.

In general, however, the use of the upper beam is to give an indirect component of light in the room. This is of sufficient intensity that with the lower beam closed off there is still sufficient light in the room for general activities. When light is wanted on the bed for any seeing purpose the lower beam is of course used. The upper beam is still used to avoid excessive contrasts between reading plane and background that would result if no indirect component was used.

Since it is obvious that the invention may be embodied in other forms and constructions within the scope of the claims, I wish it to be understood that the particular form shown is but one

of these forms, and various modifications and changes being possible, I do not otherwise limit myself in any way with respect thereto.

What is claimed is:

1. A wall mounted luminaire having a normally vertical backplate, a plate carried lamp socket having its axis horizontal, in front of the plate, and parallel with the plate, and disposed to carry a lamp in front of the plate, two forwardly extending brackets, one near the socket and apertured for the lamp, the other spaced therefrom to accommodate the lamp, bracket carried bearing members coaxial with the socket axis, a shutter member extending between the bearing members and mounted thereon, and occupying a zone of substantially 120° width with respect to said axis, the shutter being shiftable on said bearing members to place it below the axis to intercept downwardly emitted light, above the axis to intercept upwardly emitted light or to the rear of the axis to allow escape of light upwardly, downwardly and forwardly.

2. A wall mounted luminaire having a normally vertical backplate, a plate carried lamp socket having its axis horizontal, in front of the plate, and parallel with the plate and disposed to carry a lamp in front of the plate, two forwardly extending brackets, one near the socket and apertured for the lamp, the other spaced therefrom to accommodate the lamp, bracket carried bearing members coaxial with the socket axis, a shutter member extending between the bearing members and mounted thereon, and occupying a zone of substantially 120° width with respect to said axis, the shutter being shiftable on said bearing members to place it below the axis to intercept downwardly emitted light, above the axis to intercept upwardly emitted light or to the rear of the axis to allow escape of light upwardly, downwardly and forwardly, and an enclosing housing having side walls extending forwardly from the ends of the backplate, a front wall in front of the lamp shutter path and top and bottom walls apertured above and below the lamp region to allow escape of light upwardly or downwardly or both upwardly and downwardly depending upon the position of the shutter.

3. A wall mounted luminaire as claimed in claim 2, wherein the top and bottom walls converge forwardly and the front and side walls have a vertical depth substantially equal to the vertical depth of the backplate.

4. A wall mounted luminaire as claimed in claim 2, wherein the top and bottom walls converge forwardly and the front and side walls have a vertical depth substantially equal to the vertical depth of the backplate, and having light redirecting and transmitting closure plates in the apertured top and bottom walls, which closure plates are screened at angles near the horizontal by the upper and lower portions of the side and front walls.

5. In a luminaire of the point light source, wall mounted type, a lower upwardly and outwardly sloping, rectangular lens plate, an upper downwardly and outwardly sloping, rectangular lens plate, the plates intercepting light rays in pyramidal regions with the apex at the locus of the light source, each lens plate having a system of annular light concentrating prisms and an opposed system of horizontal parallel light concentrating prisms, and a focal point in front of the locus of the light source whereby the diverging light intercepted by the lens plates is

concentrated into asymmetric beams deviated forwardly of the axial lens of the plates.

6. In a luminaire of the wall mounted type, an upper prismatic light transmitting and redistributing plate, a lower prismatic light transmitting and redistributing plate, the upper plate sloping downwardly and forwardly, the lower plate sloping upwardly and forwardly, the plates being each adapted to accept a solid angle of light radiating from a locus therebetween, and having horizontal light deviating prisms and opposed annular light concentrating prisms to produce forwardly directed light beams of controlled lateral spread and at approximately 50° from the zenith and nadir respectively, for ceiling illumination and for illumination of a work area below the luminaire and distant from the luminaire mounting, the plates having high brightness in horizontal directions, and an opaque housing extending between the plates at the front and rear thereof and at the ends thereof to cut off light extraneous of that accepted by the plates, and having plate screening elements on its front and the ends of a vertical depth to intercept stray light emitted from the plates in generally horizontal directions without intercepting the dominant light rays in said beams.

7. A luminaire such as claimed in claim 6, having a shutter mounted for movement about a horizontal axis and movable from a position where it screens neither plate to positions where it screens all or selected portions of either plate.

8. A luminaire such as claimed in claim 6, having a shutter mounted for movement about a horizontal axis and movable from a position where it screens neither plate to positions where it screens all or selected portions of either plate, said shutter axis passing substantially through said locus and the shutter being reflecting and cylindrical so that when one plate is screened, the light output through the other plate is increased.

9. A luminaire as claimed in claim 6, wherein the prismatic plates are of rectangular shape, are tilted at angles of approximately 15° to the horizontal and the longitudinal prisms are of the same sign on opposite sides of median longitudinal planes normal thereto, said median longitudinal planes being in front of said locus and making angles of approximately 5° with a line connecting said locus and the centers of the annular prisms.

10. A luminaire as claimed in claim 6, wherein the longitudinal prisms near the front edges of the plates have less refracting power than those near the rear edges to divert light away from the upper and lower portions of the front of the housing.

11. A wall type luminaire having a back plate with rearwardly extending side flanges adapted to space the back plate from the wall in engagement with the flanges and form a vertical ventilation flue, a lamp socket secured in front of the plate with its axis parallel with the plate and adapted to carry an incandescent lamp in front of the back plate, a lamp box having end walls, a front wall and forwardly converging top and bottom walls, the top and bottom walls having relatively large lens openings above and below the lamp, light redirecting lenses in the lens openings, so that the lamp is totally enclosed and the heat generated thereby is confined, and a combined light screen and heat protecting housing having a vertical depth to screen the lenses against observation in horizontal directions and

end and front walls spaced from the end and front walls of the lamp box to provide side and front ventilation flues.

VEARL S. WINCE.
